(57) **CLAIM**

The ornamental design for a swimming float as shown and described.

DESCRIPTION

FIG. 1 is a front, left and bottom perspective view of a first embodiment of a swimming float, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is a front, left and bottom perspective view of a second embodiment of the swimming float.

FIG. 11 is a rear, right and top perspective view thereof.

FIG. 12 is a front elevation view thereof.

FIG. 13 is a rear elevation view thereof.

FIG. 14 is a left side elevation view thereof.

FIG. 15 is a right side elevation view thereof.

FIG. 16 is a top plan elevation view thereof.

FIG. 17 is a bottom plan elevation view thereof.

FIG. 18 is an enlarged view of detail 18 in FIG. 10.

FIG. 19 is a front, left and bottom perspective view of a third embodiment of a swimming float.

FIG. 20 is a rear, right and top perspective view thereof.

FIG. 21 is a front elevation view thereof.

FIG. 22 is a rear elevation view thereof.

FIG. 23 is a left side elevation view thereof.

FIG. 24 is a right side elevation view thereof.

FIG. 25 is a top plan elevation view thereof.

FIG. 26 is a bottom plan elevation view thereof; and,

FIG. 27 is an enlarged view of detail 27 in FIG. 19.

1 Claim, 27 Drawing Sheets
